BOOT DRIER

Edward H. Lieber, Chicago, Ill.

Application October 9, 1945, Serial No. 621,288

3 Claims. (Cl. 34—104)

1

My present invention relates to dryers and has for its object to provide a dryer for rubber and leather boots.

Another object of this invention is to provide a dryer adapted for insertion within a boot.

A further object of this invention is to provide means for maintaining a continuous circulation of heated air in and through a boot.

A still further object of my invention is to provide a boot dryer including means for suspending a boot in inverted position and means for supporting a heater beneath the open end of the boot.

Other features and advantages will become more readily apparent from the following description and the accompanying illustrative drawings in which:

Figure 1 is a sectional elevational and diagrammatic view illustrating my invention.

Figure 2 is a detail perspective view of a dryer clamp.

Figure 3 is a broken off detail view of a heater support.

Figure 4 is a detail edge view of a boot clip,

Figure 5 is a detail plan view of a baffle, and

Figure 6 is a transverse sectional view thereof.

In the above drawings as well as in the specification to follow, the same characters of reference indicate the same parts throughout.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claims. And while I have stated the primary field of utility of my invention it remains obvious that it may be employed in any other capacity wherein it may be found applicable.

In the drawings, 10 indicates a boot held suspended in inverted position by a spring clip 11, the ends 12 and 13, of which are rolled to grip over the opposite edges of the boot sole 14, at a location near the instep 15, of the boot in order to hold the same in vertical position. Through the center of the clip is secured one end 16, of a flexible device 17, having a loop 18, on its free end for attaching to a nail or the like 19.

Held suspended within the boot by means of a pair of opposing arcuate jaw members 20 and 21, supported transversely upon the outer terminals

22 and 23, of leaf springs 24 and 25, the lower ends 26 and 27, of which are welded or otherwise fixed to a clamp collar 28, adjustably secured to a pipe 29, by means of a set screw 30.

The upper end 31, of the tube 29, is curved to extend into the toe portion 32, of the boot 10. Fixed to the end 31, adjacent its terminal 33, is a flange 34, and spaced down therefrom at the ankle portion 35, of the boot is another flange 36.

Both these flanges 34 and 36, are perforated as indicated at 37, and their function is to center the tube 29, to prevent same from touching any part of the boot, which might burn the same and also to hold the boot open for free passage of air.

The lower end 39, of tube 29, is flared to funnel shape 40, and fixed to the wall 41, thereof is an end 42, of a depending support 43, to the lower terminal 44, of which is fixed a horizontally disposed pan 45, adapted to hold a candle 46, or any other heater directly under the funnel 40, whereby heat will be carried through tube 29, and emitted from its mouth 38, into the toe of the shoe from where it will pass to the heel portion 47, of the boot and then finally passes down the boot leg 48, and out through the end 49, thereof.

From the foregoing it will be apparent that I have provided an effective, quick and inexpensive means whereby boots may be dried. Hunters, trappers, fishermen, etc., very often have wet

boots, either through the elements or perspiration which makes it very hard to remove the boots and which makes such wet boots very uncomfortable to again wear before drying out and ordinarily this requires a long time, especially in the case of rubber boots. Therefore, in order to overcome this difficulty I have designed the above described dryer with which boots may be dried in a comparatively short time.

It is thought that persons skilled in the art to

which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention that which

I claim as new and desire to procure by Letters Patent is:

1. Apparatus for drying an inverted boot comprising a tube open at both ends extending from beneath said boot into the toe portion of said

boot, and means cooperating with the inner sur-

faces of said boot to define linearly arranged communicating chambers within said boot, a source of heat at the lower end of said tube, whereby heated air led through said tube into said toe portion is successively restricted against escape from the boot, said means comprising spaced apertured flanges on said tube.

2. Apparatus for drying an inverted boot comprising a tube open at both ends extending from beneath said boot into the toe portion of said boot, and means cooperating with the inner surfaces of said boot to define linearly arranged communicating chambers within said boot, a source of heat at the lower end of said tube, whereby heated air led through said tube into said toe portion is successively restricted against escape from the boot, said means comprising spaced apertured flanges on said tube and contacting said boot interiorly, one of said flanges being positioned adjacent the instep of said boot and another of said flanges being positioned adjacent the ankle portion of said boot.

3. Apparatus for drying an inverted boot comprising a tube open at both ends extending from beneath said boot into the toe portion of said boot, and means cooperating with the inner surfaces of said boot to define linearly arranged communicating chambers within said boot, a source of heat at the lower end of said tube, whereby heated air led through said tube into said toe

portion is successively restricted against escape from the boot, said means including spaced apertured flanges on said tube, said flanges contacting said boot interiorly and functioning also to locate said tube relative to said boot, further tube-locating means comprising arcuate plate members resiliently supported on said tube adapted to contact the inside of the top of said boot, a funnel on the outer end of said tube, and a candle holder secured to the funnel and depending beneath said funnel, said source of heat being a lighted candle in said holder.

EDWARD H. LIEBER.
